UNITED STATES PATENT OFFICE.

ALEXANDER W. FIELD, OF GLEICHEN, ALBERTA, CANADA.

BRAKE SHOE.

Application filed March 25, 1925. Serial No. 18,230.

My invention relates to brake shoes for vehicles wheels and the main object of the invention is to provide a shoe of simple construction for firmly holding the wooden 5 brake blocks and to construct the shoe in such a manner, that old worn out blocks may be readily exchanged for new ones, without detaching the shoe from the brake levers.

For this purpose the shoe is preferably 10 made of cast material and curved concentrically with the wheel for which it is intended. The shoe is further recessed to receive a number of wooden blocks which may be slipped in place in the shoe and retained 15 therein without danger of dislodging.

In the accompanying drawings one embodiment of the invention is illustrated, and Fig. 1 shows a fragmentary side elevation of a wagon provided with a brake forming 20 the subject matter of the present invention;

Fig. 2 is a section along line 2—2 of Fig. 1, and

Fig. 3 is a perspective view of the brake shoe seen from the under side.

25 In the drawing reference numeral 10 represents a wheel of a wagon or other vehicle and reference numeral 11 indicates the brake shoe.

The brake shoe is preferably made of cast 30 iron and has a curved bottom portion 12, the curvature of which is made with a radius somewhat greater than the radius of the wheel rim 10. The shoe has two side walls 13 standing perpendicularly to the bottom 35 12 or in other words running in radial direction as regards the wheel axis. The sides 13 terminate with inwardly bent flanges 14 of sufficient width to hold the brake blocks 15 in position in the shoe.

40 The end of the shoe, which is placed lowermost when in position, has an end flange 15' of approximately the same width as the curved flanges 14 on the side walls 13. This end flange continues at right angles to 45 the side walls 13 as at 16 and runs into the flanges 14 as best seen in Fig. 3. In this manner an abutment for the lowermost brake block 15 is formed by the end flange 15' and its continuation 16, so that the lowermost 50 block cannot fall out from the shoe.

At the upper end of the shoe the curved flanges 14 terminate as at 17, the distance from the upper end of the shoe being substantially the width of one of the brake 55 blocks 15 in order to permit the insertion of the blocks from this end. A transverse

flange 18 connecting the end walls 13 has approximately the same depth as the other transverse flange 15'. It is now evident that the blocks 15, which should not be thicker 60 than the depth of the space formed between the curved flanges 14 and the bottom 12, may be inserted one by one in the upper end of the shoe and passed along the curved flanges 14 toward the lower end of the shoe. The 65 last inserted block would have no support on its underside and for this reason an aperture 19 is provided in each of the side walls 13, through which a nail or other fastener may be driven to engage the last block 15, in 70 this manner holding the same and the other blocks in position.

About midway between the two ends of the shoe is preferably provided a piece of angle iron 20 firmly secured on the back of 75 the bottom 12 and provided with apertures 21 for attaching the same to the arm 22 of the brake lever of any suitable construction. At times it might be advisable to secure the lever 22 directly on the back of the bottom 80 12, for which purpose other apertures 23 are furnished in the bottom 12 of the shoe. It is evident that the apertures 21 in the angle iron 20, as well as the apertures 23 in the shoe itself, may be jointly used for securing 85 the same on the brake lever 22.

A practical size for these shoes for ordinary wagon wheels is about 18 inches in length, 5 inches in width transversely between the side walls of the channel, 2 inches 90 in depth of the side walls, $\frac{3}{8}$ of an inch in width and $\frac{3}{16}$ of an inch in thickness of the annular flanges 14. This will take wooden blocks approximately 2 inches thick, 4 inches wide and 5 inches long and would suit a 95 wheel rim 4 inches wide or less and it is evident that without much trouble, the blocks can be taken out from the channel and replaced by new ones.

For larger as well as for smaller wheels different dimensions will be used. The shoe 100 itself may be of cast or pressed steel or malleable cast iron.

The blocks are preferably soft wood as it 105 gives a better grip on the iron rim of the wheel but some fibre composition might at times be preferable to the wood.

This brake construction can be utilized for 110 wheels on any vehicle but is not surpassed for heavy wagons.

Having thus described the invention, what is claimed as new is:

A brake shoe comprising a back plate provided with depending side walls having inwardly directed longitudinally disposed laterally spaced terminal flanges, the lower ends of the back and side walls terminating in a recessed abutment, the side walls at their forward ends being connected by a transverse flange, the upper terminals of the terminal flanges stopping at a point remote

from the ends of the side walls to provide 10 an entrance for the successive insertion or removal of blocks, the wheel engaging surfaces thereof being exposed between the terminal flanges to permit a wheel rim to engage therewith. 15

In testimony whereof I affix my signature.

ALEXANDER W. FIELD. [L. s.]
